UNITED STATES PATENT OFFICE.

CHARLES ASKEW, OF MADISON, WISCONSIN.

MACHINE FOR GRINDING MOWER AND REAPER KNIVES.

SPECIFICATION forming part of Letters Patent No. 233,182, dated October 12, 1880.

Application filed June 11, 1880. (Model.)

To all whom it may concern:

Be it known that I, CHARLES ASKEW, of Madison, in the county of Dane and State of Wisconsin, have invented a new and useful

5 Improvement in Machines for Grinding Sickle-Bars of Reapers and Mowers, of which the following is a specification.

My invention consists in a novel construction of a rest and carrier for the sickle-bar and 10 combination and arrangement thereof with relation to the grindstone, whereby provision is made for adjusting the sickle-bar to the grinding-surface, as hereinafter described.

In the accompanying drawings, Figure 1 is 15 an elevation, partly in section, of an apparatus embodying my improvements. Fig. 2 is a top view. Figs. 3 and 4 are detail views.

Similar letters of reference indicate corresponding parts.

20 A represents the frame or table which supports the working parts. B is a standard, in the upper part of which is journaled a horizontal shaft, C, carrying at one end a grindstone, D, and provided at the other end with a crank, e, for turning it.

F is a flat bar, one end of which is pivoted to the table A. The other end of the bar F is provided with a slot, f. In this slot f works the headed shank g of a standard, G, which

30 forms a rest for the sickle-bar carrier. This carrier consists of a bar, H, connected to the standard G by a jointed shank, h, provided with a thumb-screw, J.

The carrier H is provided with clamps K, furnished with set-screws L for holding the sickle-bar M in place. The clamps K are arranged 35 to slide on the bar H so as to accommodate sickles of different lengths, and they are provided with keys or wedges n for tightening them in place on the carrier.

40 By means of the jointed shank h and the slot in the bar F the carrier H may be moved up to or away from the grindstone, or turned in any suitable position at the pleasure of the operator.

45 Having thus described my invention, I claim as new and desire to secure by Letters Patent—

The combination and arrangement, with relation to the table A and grindstone D, of the 50 pivoted slotted bar F, standard G, jointed shank h, and carrier H, as herein shown and described.

CHARLES ASKEW.
